UNITED STATES PATENT OFFICE.

CHRISTIAN HARRY LAMBERT, OF ANDERSON, INDIANA, ASSIGNOR TO THE BUCKEYE MANUFACTURING COMPANY, OF SAME PLACE.

NECK-YOKE.

SPECIFICATION forming part of Letters Patent No. 542,200, dated July 2, 1895.

Application filed May 13, 1895. Serial No. 549,040. (No model.)

To all whom it may concern:

Be it known that I, CHRISTIAN HARRY LAMBERT, a citizen of the United States, residing at Anderson, in the county of Madison and State of Indiana, have invented certain new and useful Improvements in Neck-Yokes, of which the following is a specification, reference being had therein to the accompanying drawings.

10 The object of this invention is to provide a simple, easily-made, and strong swiveled coupling between a vehicle-pole and neck-yoke which will permit all required freedom of motion; and to these ends said invention 15 consists in the neck-yoke coupling having the construction substantially as hereinafter specified.

In the annexed drawings, Figure 1 is a front view of the device; Fig. 2, a side view; Fig. 20 3, a vertical section on line α α of Fig. 1; Fig. 4, a detail perspective view of the two-part pivot-pin and the eyebolt, the parts being separated.

25 In the drawings, A designates the pole-center or eye, preferably made of leather in the usual way. To the upper edge of the same a round horizontal pin B is pivotally secured by a clip C, having a tubular portion that engages said pin, and ears c and c', depending from such portion and engaging opposite sides of the eyepiece A and attached thereto by rivets or other suitable means. The pin B is divided longitudinally upon an axial line 30 into halves, and at its transverse center has a round opening b, one-half of which is formed in each part of the pin, and in which opening is placed a bolt D, having at its lower end a round head d, that fits a corresponding enlargement formed at the lower end of the 35 opening b, and which holds the bolt from being pulled out of the latter. The tubular portion of the clip is provided with a slot c' in its upper side for the passage and oscillation of the bolt. At its upper end the bolt is provided with an eye E, to which is pivoted a 40 sleeve or ring F, adapted to be attached to the neck-yoke at its transverse center, as usual.

45 The eye E and sleeve F are connected together by a screw G, that passes through said

eye and through ears or lugs f f and projecting downward from the sleeve and engaging opposite sides of the eye. To relieve the screw G from strain, each lug f has a round projection f' upon its inner side, concentric with the screw, which fits a corresponding cavity or countersink in the side of the eye E. The sleeve F, to facilitate its attachment and removal from the eye E, and also its placing upon and removal from the neck-yoke, is divided on a longitudinal line in 55 halves, each of which has one of the lugs f. The upper edge of one of the halves abuts against a shoulder f² upon the other and is overlapped by a flange f³ on said other half.

The assemblage of the parts of my coupling 60 will be readily understood. The halves of the pin B being placed properly together with the bolt D in place, the clip C is sprung over the bolt, the eye E of the latter being passed through the slot c of said clip. The clip is 65 then riveted to the eye or center piece A, and finally the sleeve F is connected to the eye E of the bolt.

70 It will be seen that my coupling contains a universal joint, a pivotal connection existing 75 both between the pin B and eyepiece A, one between the bolt D and said pin B, and one between the bolt D and the sleeve F.

Having thus fully described my invention, 80 what I claim is—

The combination of a pole-engaging piece, a clip C secured to the upper edge of said piece and slotted at c', a two-part pin B pivotally inclosed within said clip C, the two parts of said pin being correspondingly semi-circularly notched at b, a headed-pin D pivotally resting in the opening formed by the two notches b and provided with an eye E, and a yoke-engaging part provided with ears pivotally clamped to the said eye E, substantially as described.

85 90 In testimony whereof I affix my signature in presence of two witnesses.

C. HARRY LAMBERT.
